STEERING MECHANISM

Charles V. Koons, Philadelphia, Pa., assignor to
 American Engineering Company, Philadelphia,
 Pa., a corporation of Pennsylvania

Application September 27, 1933, Serial No. 691,171

7 Claims. (Cl. 103—38)

This invention relates to steering mechanisms, and more particularly to steering mechanisms of the electro-hydraulic type employed on ships, dirigibles and the like.

One object of the present invention is to provide in a steering mechanism employing a fluid pump and motor, a safety means commonly known as a torque equalizer, which functions when the pressure in the system reaches a predetermined value to reduce the output of the pump and thereby prevent damage to the parts.

A more specific object is to provide in a device of the stated character a safety means or torque equalizer comprising a single fluid motor connected with the pressure in the system which operates against the tension of adjustable spring means to reduce the output of the pump when the pressure in the system reaches a predetermined value.

A further object is to provide a safety means or torque equalizer which is comprised of but a few simple parts compactly arranged, and which requires a minimum of space.

Other and further objects will become apparent as the description of the invention progresses.

Of the drawings:

Fig. 1 is a general plan view showing the steering mechanism comprising the present invention.

Fig. 2 is a plan view of the rudder stock and the fluid motor for operating the same.

Fig. 3 is a sectional elevational view of a portion of the control means for the pump including the torque equalizer.

Fig. 4 is a view of the torque equalizer taken substantially along line 4—4 of Fig. 3.

Fig. 5 is a plan view of the mechanism shown in Fig. 4.

Fig. 6 is a plan view of a modified construction.

Fig. 7 is an enlarged view partly in section of the upper portion of the mechanism shown in Fig. 4.

Referring to the drawings, the numeral 1 designates generally the control for the steering mechanism, which includes a variable stroke reversible discharge pump 2 of the general type shown and described in the United States patent to Albert R. Kuzlewski, No. 1,924,124. Pump 2 is driven by an electric motor M, or by any other suitable means. Fluid discharging from pump 2 operates a fluid motor 3, the rams 4 and 5 of which are operatively connected to a rudder stock 6 by links 7 and 8 respectively, as shown in Fig. 2. Ram 4 operates in aligned cylinders 9 and 10 while the ram 5 operates in aligned cylinders 11 and 12 arranged in the present instant in sub-

stantially parallel relation with cylinders 9 and 10. As shown in Fig. 1, pipes 13 and 14 leading from pump 2 are connected to distributing valves 15 and 16 respectively. Distributing valves 15 and 16 are connected to the cylinders 10, 11 and 9, 12 by pipes 18, 19 and 17, 20, respectively. Thus when pressure is applied to pipe 13 by the pump 2 fluid will enter cylinders 10 and 11, causing the rudder (not shown) to be moved in a counter-clockwise direction (Fig. 2). It is also apparent that when pump 2 is adjusted so as to deliver fluid pressure to pipe 14 fluid will enter cylinders 9 and 12, thereby causing the rudder to move in a clockwise direction. In constructions of this character when pressure is applied to either of the pipes 13 or 14, suction is applied to the other causing evacuation of the ram cylinders which are not subjected to pressure.

Steering may be effected from several desired positions located at points remote from the operating mechanism. In the present embodiment three stations are provided which are designated as A, B and C, respectively. Steering wheels 21, 22, and 23 are provided at stations A, B and C, which are respectively geared to highly sensitive generators 24, 25 and 26. Electrical conductors 27, 28 and 29 connect generators 24, 25 and 26, respectively, with the poles 30, 31 and 32 of a station switch 33. Switch 33 is connected to a single throw switch 34 by conductors 35. A second series of conductors 36 connect switch 34 with a second switch 38, and a third series of conductors 37 connect switch 38 with a highly sensitive electric motor 39. Alternating current for energizing the generators 24, 25 or 26 and motor 39 is obtained from collector rings (not shown) provided on motor M, or from any other suitable source. Conductors 43 and 44 lead from these collector rings to a switch 45 which in turn is connected to switch 38 by conductors 46 and 47. The generators 24, 25, and 26, and motor 39 are of a well known type and are so constructed that any motion imparted to any of the generators 24, 25 or 26 by the steering wheels associated therewith is simultaneously imparted to the motor 39 through the connections just described. The motor 39 is operatively connected with a speed reduction unit 48, which in turn is connected with a bevel gear 49 forming one side of a differential gear 50; a bevel gear 51 forming the other side of said differential gear being connected in the present instance through a worm wheel and worm 52 to a followup shaft 53, which in turn is operatively connected to the ram 4 by the chain and gear mechanism 54.

shown in Fig. 2. In mesh with bevel gears 49 and 51 is a third bevel gear 55. This gear has operatively connected therewith a segmental gear 56 mounted coaxial with gears 49 and 51. Segmental gear 56 meshes with a rack 57 secured to a block 58 slidably mounted upon a framework 59, secured to the top of a casing 60, which houses the differential gear 50. Spaced from block 58 and in axial alignment therewith is a second block 61 slidably mounted on framework 59. Sliding block 61 is provided with inwardly extending bosses 62, 63 and 64, which are suitably bored to receive rods 65, 66 and 67, the ends of which are threaded to receive lock nuts 68, 69 and 70, respectively, as shown in Fig. 3. Sliding block 58 is also suitably bored to receive the rods 65 and 67. Rods 65 and 67 are secured to the enlarged portions 71 and 72 respectively, of extensions 73 and 74 which extend through and are guided in openings provided in a bracket 75. Bracket 75 is secured to a supplemental framework 76 which in turn is secured to casing 60 and to the extensions 77 and 78 of the cylinder 79 of a fluid motor 80. The enlarged portions 71 and 72 of extensions 73 and 74 form annular shoulders which abut against the outer side of block 58. Rod 66 extends through an enlarged opening 81 provided in block 58 and the enlarged end thereof is provided with internal threads for receiving the reduced tapped end of a valve stem 82 extending from a fluid motor 83. Slidably mounted on the rod 66 and in close juxtaposition to the inner face of block 58 is a collar 84 having an annular boss 85 extending inwardly therefrom. A coil spring 86 extends between block 61 and collar 84 and is held in position by the bosses 63 and 65 respectively. As shown in Fig. 3, the enlarged portion of rod 66 forms an annular shoulder which is adapted to engage the outer side of collar 84. Spring 86 urges block 58 into engagement with the enlarged portions 71 and 72 of extensions 73 and 74, and block 61 into engagement with nuts 68, 69 and 70, and the tension thereof may be varied by adjusting these nuts. By this construction a resilient connection is provided between the valve and the differential gear 50 which permits relative movement thereof.

The fluid motor 83 is of the general type shown and described in the pending application of Robert C. Lamond, Serial No. 565,644, filed September 28, 1931, and for a full disclosure thereof reference may be had to said application. This motor is provided with a plunger (not shown), the extension 87 of which is pivotally connected to one end of a lever 88. The other end of lever 88 is connected to the mechanism of the pump 2 which controls the direction of discharge and the stroke thereof. Thus, when the valve of motor 83 is adjusted by the differential gear 50 upon operation of motor 39, the plunger thereof will actuate lever 88, which in turn actuates the pump adjusting mechanism causing fluid to be delivered to motor 3 to adjust the rudder accordingly. Upon movement of rams 4 and 5 of motor 3 the followup mechanism actuates the differential gear 50 in the opposite direction from which it was previously operated by motor 39, causing the valve of motor 83 to move in a reverse direction to neutral position. When this occurs the plunger operating in motor 83 actuates the lever 88 in the reverse direction, causing the stroke adjusting mechanism to return the pump 2 to neutral position. The rudder will then remain

in adjusted position until the stroke of pump 2 is again adjusted by the mechanism just described. Fluid is delivered to motor 83 by a small pump 89 driven by motor M. Pump 89 is preferably of the same general type as the pump 2, and is connected in an independent hydraulic system through the piping connections 90 and 91, shown in Fig. 1. A makeup tank A is shown in operative relation with an hydraulic system, including the pump 89 and motor 83, and this tank 10 may also supply the main fluid system including pump 2 and motor 3.

Referring to Figs. 3, 4 and 5, the bracket 75 comprises an upper semi-cylindrical casing 92 and a lower semi-cylindrical casing 93 having independent guide members 94 and 95 secured to the ends thereof. The guide members 94 and 95 are suitably secured to the supplemental framework 76 by any suitable means, which framework in turn is secured to casing 60 and the extensions 77 and 78 of fluid motor 80, as previously set forth. The semi-cylindrical casings 92 and 93 are secured together by any suitable means, such as by bolts 96, forming a cylindrical casing 97, as shown in Figs. 3 and 4. Mounted within this casing is a split sleeve 98 which surrounds the reduced portion 99 of valve stem 82, and the shoulders 100 and 101 formed by the reduced portion of the valve stem abut against the ends of said sleeve thereby providing a driving connection between the latter and the stem 82. By this construction it is seen that upon reciprocation of sleeve 98 by mechanism which will be presently described, axial adjustment of valve stem 82 in either direction is effected. As shown more particularly in Fig. 4, a pair of studs 102 and 103 are tightly pressed into apertures provided in diametrically opposite points in sleeve 98. The enlarged portions 104 and 105 of studs 102 and 103 respectively, extend through and are guided in slots 106 and 107 of casing 97. Ball bearing rollers 108 and 109 are provided on studs 102 and 103 respectively, near the outer ends thereof, which are held in place by lock nuts 110 and 111. These rollers are adapted to be engaged by the cam faces 112 or 113 provided in arms 114 and 115 respectively, of a yoke 116, when the latter is actuated by motor 80, as will presently appear. Yoke 116 is guided for reciprocation between the inner faces of guide members 94 and 95 of bracket 75. A cross member 117 connects the arms 114 and 115 of yoke 116, and is secured intermediate the ends thereof to a piston 118 operating in the cylinder 79 of motor 80. A pair of links 119 and 120 are pivotally connected at one end thereof to the cross member 117, and at the other end to one arm of bell crank levers 121 and 122, respectively. Bell crank levers 121 and 122 are pivotally mounted in brackets 123 and 124, respectively, and the other arms thereof have pivoted thereto one end of rods 125 and 126, respectively, which extend through apertures provided in a spring seat 127 pivotally mounted in a pair of spaced bearing brackets 128 and 129, as shown in Fig. 5. A pair of coil springs 130 and 131 encircle rods 125 and 126, respectively, and extend between spring seat 127 and a pair of spring seats 132 and 133 provided near the outer ends of said rods. Lock nuts 134 and 135 provided at the ends of rods 125 and 126 maintain the springs in proper position on the rods and afford a means for adjusting the tension of said springs.

Fluid motor 80 is connected to the pressure in the system by a pipe 136, which, as shown in Fig. 1, is connected to pipes 137 and 138 leading respectively from distributing valves 15 and 16. It therefore is seen that when the pressure in the system exceeds the tension of springs 130 and 131 piston 118 will actuate yoke 116 causing the cam faces 112 or 113 thereon to engage rollers 108 and 109, and thus adjust the valve 10 of motor 83 to normal position. When this occurs motor 83 will actuate the stroke adjusting elements of pump 2 to neutral position thereby rendering the pump ineffective. Under certain conditions it may be desirable to place the pump 15 on partial stroke rather than in neutral position and this may be accomplished by so designing the cam faces of 112 and 113 that the valve will be actuated only a portion of the distance between full stroke and neutral position. In the 20 event that frequent changes are required adjustable cam faces may be provided. It will be noted that when valve stem 82 is operated by cams 112 or 113 this operation takes place through the spring connection 86, and therefore relative 25 movement of valve stem 82 and the differential gear 50 is permitted. The spring connection 86 thus prevents damage to the parts when the valve is operated by yoke 116; also in case the differential gear overtravels the distance required 30 to move the valve to its limiting position in either direction.

The operation of the mechanism just described is briefly as follows. Suppose, for example, that steering is to be effected from station A. The contact arm of station switch 33 is first adjusted so as to make contact with the pole 30 thereon. Now, upon manipulation of steering wheel 21 in either direction the motion imparted thereby to generator 24 is immediately transmitted to 40 motor 39 through the conductors 27, 35, 36 and 39, and switches 33, 34 and 38. Motor 39 through reduction gearing 48 actuates the bevel gear 49 of the differential gear 50, causing the bevel gear 55 to revolve about its axis with the 45 result that segmental gear 56 associated therewith will actuate rack 57 and consequently sliding block 58. The movement thus imparted to sliding block 58 is imparted to valve stem 82 through the spring mechanism 86 shown in Fig. 3. Upon adjustment of the valve stem 82 of motor 83 in this manner fluid from pump 89 will 50 actuate said motor which in turn actuates lever 88 and places pump 2 on stroke. Fluid from pump 2 is now delivered to motor 3 which, 55 through links 7 and 8, adjusts the rudder. Upon movement of the rams 4 and 5 of motor 3, the followup shaft 53 will be operated by the mechanism 54 which through the worm and worm wheel 52 causes rotation of bevel gear 51 of the differential gear 50. This movement of the bevel gear 51 causes bevel gear 55 to revolve in the opposite direction from which it was previously operated by bevel gear 49, thereby causing the rack 57 to operate the sliding block 58 and valve stem 82 in the reverse direction to neutral position. This causes motor 83 to operate in the reverse direction which, through its connection with the stroke adjusting mechanism of pump 2, 65 causes the latter to be adjusted to neutral position. The rudder thus remains in adjusted position until steering wheel 21 is again operated.

It frequently occurs, especially during a heavy sea, that excessive forces are imposed against the 70 rudder which react through the hydraulic sys-

tem, causing the pump 2 to generate excessive pressure in the system which may cause damage to the operating parts. To prevent such damage, I have devised an improved safety means or torque equalizer which functions when excessive pressures occur, to reduce the stroke of pump 2 thus relieving the operating effort of the motor M. As shown in Fig. 1, the fluid motor 80 is connected at all times to the pressure in the system, and when this pressure exceeds the tension of 10 springs 130 and 131 (Figs. 4 and 5) piston 118 actuates yoke 116 causing the cam 112 or 113 provided thereon to engage rollers 108 and 109 to adjust valve stem 82 to neutral position or to a position intermediate neutral position and full 15 stroke position, as the case may be. The motor 83 then operates to reduce the stroke of pump 2 accordingly.

The motor 83 is employed only in larger units where considerable pressure is required to adjust the discharge and stroke adjusting mechanism of the pump. In smaller units the mechanism shown in Fig. 6 may be effectively employed. This mechanism is similar in all respects to that shown in Fig. 1 except that the motor 83 is dispensed with and instead a reciprocating rod 82' is directly connected to one end of a lever 88', the other end being connected to the stroke and discharge adjusting device of pump 2'. Rod 82' is actuated by a differential gear 50' through 25 a spring mechanism 86' of the same construction as that shown in Figs. 1 and 3. Rod 82', and consequently the stroke adjusting mechanism, is also adjusted to reduce the stroke of pump 2' when the pressure in the system reaches a predetermined value, by a yoke 116' operated by a fluid motor 80' of the same construction as that shown in Figs. 2, 3 and 4.

As shown in Fig. 1, a trick wheel 140 is also provided which enables steering of the ship independently of the motor 39. Trick wheel 140 is operatively connected to the reduction gear 48 by the mechanism indicated generally by the numeral 141. When steering is effected from stations A, B or C, the trick wheel 140 may be disconnected by disengaging a clutch 142.

While the mechanisms herein described are admirably adapted to fulfill the objects primarily stated, it is understood that it is not intended to confine the invention to the embodiments herein shown, since it may be embodied in other forms, all coming within the scope of the claims which follow.

What is claimed is:

1. In a device of the class described, the combination with a pump, of means for regulating the discharge of said pump including a reciprocable member and a differential gear, resilient means interposed between said differential gear and said member, projections extending laterally from said member, a yoke having cam faces thereon adapted to engage said projections, a fluid motor for actuating said yoke against the tension of said resilient means when the pressure developed by the pump exceeds a predetermined value, to reduce the stroke of the pump, one or more springs for resisting the operation of said fluid motor, a bracket mounting for said springs, means including a lever operatively connecting said springs to said yoke, and means for adjusting said springs.

2. In a device of the class described, the combination with a pump, of means for regulating the discharge of said pump including a movable member, a pair of spaced abutments on said

member, complementary elements engaging said member and extending between said abutments, a casing enclosing said complementary elements and having provided therein a pair of diagonally opposed guide slots extending longitudinally thereof, a pair of studs secured to and extending outwardly of said complementary elements, and guided for movement in said slots, and means for engaging said projections to actuate said movable member when the pressure developed by said pump exceeds a predetermined value, to thereby reduce the discharge of said pump.

3. In a device of the class described, the combination with a pump, of means for regulating the discharge of said pump including a movable member and a differential gear, resilient means interposed between said differential gear and movable member, a pair of spaced abutments on said member, complementary elements engaging said member and extending between said abutments, a casing enclosing said elements and having provided therein, a pair of diagonally opposed guide slots extending longitudinally thereof, a pair of studs secured to and extending outwardly of said complementary elements and guided for movement in said slots, and means for engaging said studs to actuate said movable member against the tension of said resilient means when the pressure developed by said pump exceeds a predetermined value, to thereby reduce the discharge of said pump.

4. In a device of the class described, the combination with a pump, of means for regulating the discharge of said pump including a reciprocable member, resilient means operatively connected to said member whereby movement of the latter is effected through said resilient means, a pair of spaced abutments on said member, complementary elements engaging said member and extending between said abutments, a casing enclosing said complementary elements and having provided therein a pair of diagonally opposed guide slots extending longitudinally thereof, a pair of studs secured to and extending outwardly of said complementary elements, each of said studs having a portion thereof extending through and guided in said slots, anti-friction means provided at the outer ends of each of said studs, and means for engaging said anti-friction means to reciprocate said member against the tension of said resilient means when the pressure developed by said pump exceeds a predetermined value to thereby reduce the discharge of said pump.

5. In a device of the class described, the combination with a pump, of means for regulating the discharge of said pump including a reciprocable member, a pair of crossheads mounted on said reciprocable member, resilient means extending between said crossheads whereby movement of said member is effected through said re-

silient means, a pair of spaced abutments on said member, complementary members engaging said member and extending between said abutments, a casing enclosing said complementary elements and having provided therein a pair of diagonally opposed guide slots extending longitudinally thereof, a pair of studs secured to and extending outwardly of said complementary elements, each of said studs having an enlarged portion extending through and guided in said slots, a roller mounted at the outer end of each of said studs, and means for engaging said rollers to actuate said reciprocable member against the tension of said resilient means when the pressure in said pump exceeds a predetermined value, to reduce the discharge of said pump, said last mentioned means comprising a pair of cam members, a fluid motor connected to the pressure of said pump for actuating said cam members, and resilient means for resisting movement of said cam members in one direction, and to return the latter to ineffective position when the pressure developed by said pump falls below said predetermined value.

6. In a device of the class described, the combination with a pump, of means for regulating the discharge of said pump including a movable member and a differential gear, a flexible connection between said member and gear, projections extending laterally from said movable member, a yoke having cam faces thereon adapted to engage said projections, a fluid motor for actuating said yoke when the pressure developed by the pump exceeds a predetermined value, to reduce the stroke of said pump, one or more springs for resisting the operation of said fluid motor, said springs being disposed at an angle to said yoke, a bracket mounting for said springs, means including a bell crank lever operatively connecting said springs and said yoke, and means for adjusting said springs.

7. In a device of the class described, the combination with a pump, of means for regulating the discharge of said pump including a movable member, mechanism for actuating said movable member, resilient means interposed between said operating mechanism and said member, projections extending laterally from said movable member, a yoke having cam faces thereon adapted to engage said projections, a fluid motor for actuating said yoke against the tension of said resilient means when the pressure developed by the pump exceeds a predetermined value, to reduce the stroke of said pump, one or more springs for resisting the operation of said fluid motor, said springs being disposed at an angle to said yoke, a bracket mounting for said springs, and means including a bell crank lever operatively connecting said springs and said yoke.

CHARLES V. KOONS.
